UNITED STATES PATENT OFFICE.

HARRY W. BRINTNALL, OF CHICAGO, ILLINOIS, ASSIGNOR OF ONE-HALF
TO FELIX A. VENNEY, OF DALLAS, TEXAS.

PAPER-SEPARATOR.

No. 802,679.

Specification of Letters Patent.

Patented Oct. 24, 1905.

Application filed March 27, 1905. Serial No. 252,286.

To all whom it may concern:

Be it known that I, HARRY W. BRINTNALL, a citizen of the United States, residing at Chicago, in the county of Cook and State of Illinois, have invented a new and useful Improvement in Paper-Separators, of which the following is a specification.

My invention relates particularly to mechanism for separating sheets of paper of the general character described in Patent No. 747,864, granted December 22, 1903.

My primary object is to simplify the mechanism required for the purpose indicated and insure greater certainty in the separating operation.

The invention is illustrated in the accompanying drawings, in which—

Figure 1 represents a broken elevational view of sheet - separating mechanism constructed and operating in accordance with my invention; Fig. 2, a similar view showing another position of the parts and illustrating the manner in which the one edge of the body of the uppermost sheet of paper is by a straightening or stretching process raised above the pile to enable an air-blast to complete the separating operation; and Fig. 3, a detail view showing the method of adjusting the tension upon the friction paper-engaging rolls employed.

In the construction shown in the patent above referred to, as well as in certain other constructions known to me, paper-engaging fingers are employed, which work toward each other in a paper-buckling operation, and stops are employed for holding the paper at points near the buckling-fingers, together with mechanism for actuating the stops. In this construction, owing to the necessity of arranging the paper-stops close to the buckling-fingers, uncertainty and lack of positiveness in the paper - separating operation is experienced, particularly on days which are favorable to the development of an annoyingly large amount of frictional electricity in the paper. The result is that two sheets of paper are sometimes fed at one time or the paper is torn, necessitating the frequent stoppage of the machine in connection with which the paper-separator operates, thereby causing great loss and annoyance.

It is the object of my invention to obviate the difficulties mentioned, and I am able by

the adoption of a simple expedient not only to simplify the separating mechanism but to render the separating operation exceedingly positive and reliable. To accomplish this result, I provide mechanism with paper-engaging fingers having working strokes away from each other, so that the top sheet of paper will be straightened and lifted from the pile, the corners of the pile of paper being wedged up to produce a hollow between them, across which the top sheet of paper is stretched during the working strokes of the fingers, enabling a centrally-directed air-blast to complete the separation of the topmost sheet from the pile.

The mechanisms employed for effecting the movements of the paper-engaging fingers may be of any desired construction. I have illustrated a known construction of such mechanisms, and it is only necessary to make plain the novel arrangement of the mechanisms with little reference to details of construction, except as to novel features therein.

A and B represent paper-engaging fingers, and A' B' the mechanisms for actuating the same. The mechanisms A' and B' are reverse duplicates—that is, they are similar mechanisms; but one is a right and the other a left mechanism. The mechanisms are supported in the usual manner above a table C, upon which are the sheets c, constituting a paper pile. The mechanisms may be regarded as arranged above the front margin of the table near the ends thereof. Wedges D D' are introduced to sustain the corners of the pile of sheets of paper in elevated positions, thereby maintaining high points d d' at two corners of the uppermost sheet, while the margin of the sheet between said corners occupies a depressed plane d². The fingers A and B work against the inclines of the pile of paper and by their frictional engagement with the uppermost sheet straighten said sheet, so that it will span the hollow between the raised points in the manner shown in Fig. 2, thereby separating the margin of the sheet from the pile by a space d³. This gives room for the injection of an air-blast through a nozzle d⁴, arranged just in front of the pile of sheets and with its orifice directed to the space d³. The air-blast, which is supplied from any suitable source, (not shown,) serves to complete the separation of the uppermost sheet from the

pile, enabling it to be withdrawn and fed to the printing-machine (for instance) in the usual manner.

Each of the finger-actuating mechanisms A' and B' comprises a frame f' , in which is journaled a shaft f'' , equipped with cams f''^2 f''^3 , an arm f''^4 , pivotally connected with said frame, joined to and actuating the corresponding paper-engaging finger and actuated by the cam f''^2 , and an arm f''^5 , actuated by the cam f''^3 and serving to actuate a finger-lifting rod f''^6 , joined to the finger near its free extremity. A spring f''^7 , encircling the rod f''^6 , holds the finger depressed during its working stroke. The shafts f' are actuated in unison by any suitable means. (Not shown.) Inasmuch as these mechanisms form portions of well-known mechanisms which are shown, for instance, in the above-mentioned patent, further description here is unnecessary. It is sufficient to say that the mechanisms are arranged and timed to give to the fingers A and B working strokes away from each other and to lift the fingers from the paper and return them to their initial positions at the proper time.

Inasmuch as it is a fact that in practice it is necessary to give to the fingers a working stroke which is greater than actually is required to straighten the top sheet of paper, I provide means to prevent tearing of the sheet, comprising a friction-roller g , preferably of rubber, journaled on a threaded stud g' , projecting laterally from the free end of the paper-engaging finger, the roller being confined on a bushing between collars g^2 . The stud is equipped with a nut g^3 , which serves to adjust the tension of a spring g^4 , which bears against the bushing. Thus it will be seen that while the roller is free to rotate on its journal still it is yieldingly held, so that the roller will exert the necessary force to straighten the sheet of paper and then roll upon the paper until the working stroke of the finger is completed.

Any suitable means may be employed for actuating the fingers, and any suitable detail of construction for enabling idle movement of the rollers after the paper has been straightened may be adopted.

What I regard as new, and desire to secure by Letters Patent, is—

1. The combination with means of supporting a pile of paper and holding the paper ele-

vated at two points, of two suitably-actuated paper-engaging means having working strokes away from each other and serving to straighten the uppermost sheet and cause it to span the space between the elevated points, for the purpose set forth. 55

2. The combination with means of supporting a pile of paper and holding the paper elevated at two points, of two suitably-actuated paper-engaging means having working strokes away from each other and serving to straighten the uppermost sheet and cause it to span the space between the elevated points, and a nozzle having an orifice located between the elevated points of the paper to direct a blast beneath the top sheet, for the purpose set forth. 60 65

3. The combination of paper-supporting means, means for sustaining certain points in the paper above the general level, thereby producing a depressed plane bounded by inclines, a pair of fingers engaging the paper near the inclines, and mechanisms serving to move the fingers away from each other up the inclines, thereby to straighten the uppermost sheet, and serving then to lift the fingers and return them to their initial positions, for the purpose set forth. 70 75 80

4. The combination with means for supporting sheets of paper with the body thereof on a given level and certain points thereof elevated, of a pair of fingers having working strokes away from each other, and yieldingly-held paper-engaging rollers supported on said fingers, whereby the rollers will turn after the paper has been straightened to enable the working stroke to be completed without injury to the paper, for the purpose set forth. 90

5. The combination with paper-supporting means, of fingers provided with lateral journals, rollers journaled thereon, springs bearing against said rollers, nuts confining said springs, mechanisms serving to move said fingers away from each other while maintaining the rollers in contact with the paper and then lift the fingers and return them to their original position, and an air-injecting nozzle located between said mechanisms, for the purpose set forth. 95 100

HARRY W. BRINTNALL.
